[57] **CLAIM**

The ornamental design for a voice activated water faucet control unit, as shown and described.

DESCRIPTION

FIG. 1 is a front plan view of the voice activated water faucet control unit of the present invention;

FIG. 2 is a rear plan view of the voice activated water faucet control unit of FIG. 1;

FIG. 3 is a left side plan view of the voice activated water faucet control unit of FIG. 1;

FIG. 4 is a right side plan view of the voice activated water faucet control unit of FIG. 1;

FIG. 5 is a top plan view of the voice activated water faucet control unit of FIG. 1; and,

FIG. 6 is a bottom plan view of the voice activated water faucet control unit of FIG. 1.

The broken line showing of words and numbers is for illustrative purposes only and forms no part of the claimed design.
